Specification for Design.

Patented Dec. 14, 1920.

Application filed November 26, 1919. Serial No. 340,869. Term of patent 7 years.

To all whom it may concern:

Be it known that I, FRANÇOIS RICHARD, citizen of the French Republic, residing at Cleveland, in the county of Cuyahoga and State of Ohio, have invented a new, original and ornamental Design for an Automobile-Fender, of which the following is a specification, reference being had to the accompanying drawing, forming part thereof.

Figure I and Fig. II are perspective views of my automobile fender design, the

relative positioning of the same being made clear in each figure by indicating in dotted lines the front outline of an automobile engine hood.

I claim:

The ornamental design for an automobile fender as shown.

FRANÇOIS RICHARD.
